A CORPORATION OF NEW YORK

STRAINER

Application filed August 16, 1928. Serial No. 300,034.

This invention relates to strainers for liquids and is an improvement over the form of strainer disclosed in a copending application, Serial Number 209,455, filed July 30, 1927. In strainers of this kind a structure is provided for with a duplicate set of strainer screens for the arresting of dirt or other foreign particles in the liquid to be strained, which structure is equipped with means by which one of the strainer screens can be cut out for cleaning or repairing without interrupting the flow of the liquid through the other screen. In the application above referred to, the strainer structure has a single air or steam blow-out connection, and each screen and its chamber has a separate drain connection, the cut-out means admitting a purging medium through the steam or air connection to that particular strainer screen only which is not in use. This purging medium is then discharged through the drain connection which communicates with the screen that is being purged. It is the particular object of the invention to provide cut-out means for either one of the screens which not only admit the purging medium to that screen which is not in use, but simultaneously open a single drain connection with which the structure is provided, and permit the blowing out of that screen without manipulating separate drain plugs or valves for each of the two screens.

In the drawings, Fig. 1 is a vertical sectional view through a strainer structure showing a preferred embodiment of the invention; Fig. 2 is a horizontal sectional view along the plane of line 2—2 in Fig. 1; Fig. 3 is a horizontal fragmentary sectional view along the plane of line 3—3 in Fig. 1; Fig. 4 is a horizontal sectional view along the plane of line 4—4 in Fig. 1; and Fig. 5 is a vertical cross sectional view along the plane of line 5—5 in Fig. 4. Like characters of reference denote similar parts throughout the several views and the following specification.

10 is a hollow casing of substantially oblong shape. 11 is a bridge wall extending across the upper part of the inside of the casing 10 dividing the same into a lower or

inlet chamber 12 and an upper or outlet chamber 13. Symmetrically disposed at each side of the top of the casing 10 is a hollow cap 14, closed at its top, projecting through the outlet chamber 13, and being threaded into the wall 11 at 15, a shoulder 16 making a tight seat against the top of the casing. The vertical wall of the cap 14 between the top of the casing and its wall 11 is provided with opening 17. The lower end of the cap 14 terminates in a cylindrical extension 18 somewhat smaller in its outer diameter than the threaded portion 15. 19 is a cup-shaped strainer basket made of perforated sheet metal or the like, having its open end fitted tightly over the extension 18. Casing 10 is provided at its front with a cylindrical extension 20, internally threaded at 21 for a pipe, in communication with the outlet chamber 13 by passages 22, 23 and 24. Casing 10 is provided with a similar extension 25 at its back, similarly threaded at 26, this extension being in communication with the inlet chamber 12 by passages 27, 28, 29 and 30.

31 is a tapering cut-out, rotatably fitted in the casing 10, preferably centrally between caps 14, between its top wall, wall 11 and its bottom wall. 32 is a solid wall extending across the central part of the key 31 about in line with wall 11 of the casing 10. The upper part of the key 31 between the top wall of casing 10 and wall 11 has a substantially rectangular opening 33 into a hollow center 34. This opening is of such width that it forms a continuous passage from opening 23 to opening 22, or from opening 24 to opening 22 when rotated $\frac{1}{4}$ revolution. Attention is particularly drawn to the fact that when openings 23 and 22 are in communication through hollow center 34, a solid wall 35 of the key 31 closes opening 24, and vice versa, when rotated $\frac{1}{4}$ revolution, wall 35 closes opening 23, while openings 22 and 24 are registering through the hollow center 34. The lower part of the key 31 terminates in a plug 60 which has a solid wall 36 fitted tightly in the bottom of the casing 10. A vertical central partition 37 connects wall 32 with end 36 of the key 31. This partition is so disposed that it connects

openings 28 and 29 while cutting out opening 30 when the upper part of the key 31 connects opening 22 and 23, and similarly connects openings 29 and 30 and cuts out opening 29 when rotated $\frac{1}{4}$ turn, while its upper part connects openings 22 and 24. The plug 60 is hollow below wall 36, having an open central port 61. 62 is a port through the sides of plug 60, and 63 and 64 are ducts from the chamber 12 diametrically disposed through both sides of the walls within which plug 60 is fitted and disposed in the same horizontal plane as port 62. Port 62 is of such width that it registers with duct 63 in one position and with duct 64 when rotated a $\frac{1}{4}$ revolution. 65 is an outlet at the bottom of the strainer 10 below port 61 at the bottom of plug 60. 66 is a valve which may be screwed into this outlet 65, if so desired. 20 Attention is particularly called to the fact that while only one of the ducts 63 or 64 communicates with port 62 at any one time, either one or the other is always in communication with outlet 65 by way of port 61. 38 is an outwardly projecting spindle of key 31 having its terminal D-shaped to receive a correspondingly shaped socket of a handle bar 39. This bar has a downwardly projecting lug 40 adapted to travel alongside the front 25 of the casing 10 in a segmental path 41 and is limited in its travel to a $\frac{1}{4}$ revolution by the ends 42 of the path 41 which is partially cut in the outer wall of casing 10. 42^a is a bonnet over spindle 38 screwed into the top of casing 10 and 43 is a stuffing box nut. 44 is a spring pressing against the top of the cut-out key 31 to cause its sides to fit tightly against their bearings in casing 10. In the rear of the casing on top of extension 25 is a 30 boss 45 threaded to receive an elbow connection 46 and a valve 47. 48 is a circumferential groove in part of the upper wall 35 in communication with boss 45 and connection 46 through an angularly disposed duct 49. 45 This groove is so arranged as to register with opening 24 only when the same is cut off from registering with opening 22 by wall 35, and similarly, when key 31 is rotated $\frac{1}{4}$ turn, groove 48 registers with opening 23. In both 40 positions, however, groove 48 is in communication with elbow connection 46 through duct 49. Also, while groove 48 registers with opening 24, port 62 registers with duct 64, and with duct 63 only when groove 48 registers with opening 23.

The operation of the strainer is as follows: When the strainer is in the position shown in the drawings, oil or other liquid to be strained is admitted under pressure through a pipe 60 screwed into extension 25, thence through duct 27 and opening 28, past wall 37 of the lower part of the key 31 and opening 29 into the lower or inlet chamber 12, at the left side of casing 10. The oil then passes through the 65 strainer basket 19 which being of very fine

mesh causes any impurities or other foreign matter to accumulate around its outside. The clean oil is forced through the openings 17 in the cap 14 into the upper or outlet chamber 13 at the left side of the casing and thence 70 through opening 23 into the hollow upper center 34 of the key 31, and thence through opening 22 into a pipe screwed into extension 20. Openings 22 and 23 and openings 28 and 29 are of substantially the same area, as is also 75 the passage for the oil through hollow center 34 and the space alongside partition 37. The passages in the upper part of the key 31 and openings 22 and 23 are wider and shorter 80 than the passages in the lower part of the key and openings 28 and 29 which are relatively longer and narrower because of the tapering shape of the key and the importance of keeping these passages of a uniform area.

In the position indicated in the drawings 85 and just now described, oil is admitted into the left side of the casing and discharged therefrom by virtue of the cut-out key 31 which deflects the flow of oil to and from that side of the casing, and the handle bar 39 is 90 so attached to the spindle 38 of the key 31 that it points toward the left side of the casing which serves to indicate that the left side strainer is functioning as such. The lug 40 is pushed tightly against the left hand terminal 42 of its travel. In this position, openings 24 and 30 at the right side of the casing adjacent the key 31 are cut out by, respectively, walls 35 and 37. Opening 24 is symmetrically disposed at the right side of key 31 to opening 23 and is of the same size and, similarly, opening 30 to opening 29. No oil therefore passes into the right hand side of the casing and through the right hand strainer basket 19. The right hand strainer can now 100 be cleaned easily by admitting steam, air or any other suitable purging medium through valve 47, elbow connection 46, duct 49 and groove 48 into the inlet chamber 12 at the right hand side of the casing and through 105 openings 17 into the inside of the strainer basket. Here it forces all foreign matter around the outside of the basket away from the screen and blows it out through duct 64, port 61, and outlet 65, its valve 66 having 110 been opened for that purpose. This blowing out can be achieved very efficiently because the purging agent is blown through the strainer mesh in a direction opposite to the normal flow of the oil whereby all sediment caked 115 around the outside of the basket is very quickly loosened. The groove 48 does not communicate with the left hand side of the strainer; therefore the purging agent does not enter 120 that side and its functioning is not interfered with, and similarly, duct 63 is closed by the wall of plug 60 which effectively seals the drain outlet of the left hand side of the strainer. By giving the handle bar 39 a $\frac{1}{4}$ turn 125 to the right to the end of its travel as fixed 130

by lug 40, the above described position and functioning is exactly reversed, and instead of the left hand strainer working and the right hand strainer being cut out, the right hand strainer is working and the left hand strainer cut out. The handle bar 39 pointing toward the right side of the casing indicates that the right hand strainer is functioning. In this position then, the left hand strainer can be blown out exactly in the manner described before in reference to the right hand strainer basket. In other words, that strainer which is cut out of service can be cleaned by simply opening the control valve for the purging medium attached to the casing and permitting the purging medium to blow out the impurities through the single outlet at the bottom of the strainer. It is impossible to admit a purging medium into the working strainer, nor open its drain outlet, because the peculiar arrangement of passages and ducts in the key permit of cleaning and blowing out of that strainer screen only which is cut out of service.

5 It is obvious that while we have shown the common drain outlet 65 controlled by a valve 66, this valve may be entirely dispensed with and the impurities blown out by simply opening valve 47. Various other changes in the form, proportions and minor details of construction may be resorted to without departing from the principle or sacrificing any of the advantages of the invention as defined in the appended claims.

35 What we claim as new, is:

1. A strainer for liquids comprising a structure having an inlet, an outlet, a purging connection, a single drain connection for both screens, a pair of strainer screens interposed in passages between the said inlet and outlet, and a key having means for shutting off one of the screens from the said inlet and outlet and means admitting a purging medium from the said purging connection to that screen only which is shut off for blowing out accumulated sediment through the said drain connection and a wall over the said drain connection permitting cleaning of that screen only which is shut off.

50 2. A strainer for liquids comprising a structure having an inlet, an outlet, a purging connection, a drain connection, a pair of strainer baskets interposed in passages between the said inlet and outlet so that the liquid from the inlet will be admitted around the outside of the basket to the inside thereof and thence to the outlet, and a key having means for shutting off one of the baskets from the said inlet and outlet and means for admitting a purging medium from the said purging connection to the inside of that strainer basket only which is shut off, the said key having a wall to block passages in the structure whereby the drain connection is

sealed toward that basket which is not shut off.

In testimony whereof we have hereunto set our hands.

ALBERT W. MORSE.
WALTER E. WOLLHEIM.
